J. A. MORRISON

CROSSING SIGNAL

Original Filed Dec. 4, 1926

UNITED STATES PATENT OFFICE.

JOHN A. MORRISON, OF SEATTLE, WASHINGTON, ASSIGNOR TO SAFETY SIGNAL COMPANY, A CORPORATION OF WASHINGTON.

CROSSING SIGNAL.

Original application filed December 4, 1926, Serial No. 152,622. Divided and this application filed July 23, 1927. Serial No. 207,948.

This invention relates to railway crossing signals. The present application is a division of my co-pending application, Serial No. 152,622, filed on the 4th day of December, 1926, and is intended to cover novel means for causing a signal to be thrown into operation by an approaching train, irrespective of the particular type of signal employed.

10 In order that the relationship of the wiring of the control mechanism, and the signal, may be clearly understood, I have illustrated, in the diagrammatic figure shown in the accompanying drawing, the signalling mechanism of my parent application, associated with the control device of the present application.

Referring now more particularly to the drawings, it will be seen that the signal mechanism comprises a motor 11, a siren whistle 12, and illuminating elements 13. The numeral 14 generally designates the armature shaft of the motor which is extended at one end to provide a drive for a blower 15 for operating the siren whistle and at its opposite end to provide a mounting for the governor mechanism, generally indicated at 16.

A shaft 4 is driven by conventional worm gearing, indicated at 17, from shaft 14, and upon said shaft 4 is mounted a pair of insulating disks 20 and 21, each having an arcuate contact 22. Associated with the disk 20 are brushes 23 and 24, one of which is connected to one terminal of the motor by a wire 25 and the other of which is connected to a feed wire 26 by a wire 27. With the disk 21 a feed brush 28 and a pair of discharge brushes 29 are associated. The feed brush 28 is electrically connected with the wire 26 while the discharge brushes 29 are connected by wires 30 with the illuminating elements 13.

The governor mechanism provides means for shifting the conductor disk 31, with which brushes 35 and 37 coat, the brush 35 being connected with the same terminal of the motor as the brush 23 by a wire 36, while the brush 37 is electrically connected with the wire 26. A second feed wire 38 is connected with the second terminal of the motor and

with the second terminals of the illuminating elements 13 by a wire 39.

The operation of the mechanism above described is as follows: When the wires 26 and 38 are energized, the motor 11 is energized, causing rotation of the armature shaft 14. If, at this time, the arcuate contact 22 does not connect the brushes 23 and 24, the speed of the motor will be slow, due to the fact that any increase in speed will cause separation of the disk 31 from the brushes 35 and 37. By the operation of the motor, air is forced from the fan 15 to the siren whistle 12, causing its operation at a relatively low pitch. At the same time, the shaft 14 is rotated, with the result that the disk 20 will bring its contact 22 into engagement with the brushes 23 and 24, shunting the brushes 35 and 37 so that the motor may speed up and cause a variation in the pitch produced by the siren whistle. This rotation of the shaft 14 will also bring the contact 22 of the disk 21 into engagement with the feed brush 28 and discharge brushes 29, causing the illuminating elements 13 to be energized for a short period.

The control mechanism constituting the novel subject matter of the present application comprises adjacent track sections, 40 and 41, 42 and 43, and 44 and 45, corresponding rails of the sections being insulated from one another, as at 46. A suitable source of energy, generally designated at 47, has one terminal thereof electrically connected with the rail section 43 by a wire 48. This terminal is also connected with contacts 49, 50 and 51 associated with the rail sections 41, 43 and 45. The rail section 42 is connected with the wire 26 and the rail sections 40, 42 and 44 have associated therewith contacts 49^a, 50^a and 51^a corresponding and complementary to the contacts 49, 50 and 51. The second terminal of the source of current is electrically connected with one terminal each of a pair of electro-magnets 52 and 53, and with a switch contact 54. The contacts 49^a and 51^a are each connected with the second terminal of the electro-magnet 52, as at 55, while the second contact of the electro-magnet 53, is electrically connected, as at 56, with the contact 50^a.

The armature 57 of the electro-magnet 52 is operatively connected with one arm of a pivoted bell crank 58, the other arm of which has a notch 59 for receiving and latching a gravity operated switch blade 60 to maintain the same out of engagement with the contact 54. This switch blade is operatively connected with the armature 61 of the electro-magnet 53 and is electrically connected with the feed wire 38.

The operation of the signal control mechanism is as follows: As a train enters the signalling area, it electrically connects one pair of the pairs of contacts 49, 49^a or 51, 51^a. Assuming the contacts 49, 49^a are electrically connected, a circuit is established as follows: Through the wire 48 and contact 49 through contact 49^a and wire 55 to one terminal of the electro-magnet 52, and from the second terminal of the electro-magnet 52 to the battery through the wire 62. The armature 57 of the electro-magnet 52 is thus attracted, swinging the bell crank lever 58 to the position shown in dotted lines and permitting the switch blade 60 to engage with the contact 54. This completes the connections between the lead wire 38 and the battery and since the connections between the wire 26 and the battery are open only by the spacing of the rail sections 42, 44, when the train engages these rail sections and electrically connects the same, the circuit to the signal will be completed. As the train moves over the sections 42 and 43, it closes the connection between the contact 50 and 50^a, thus completing a circuit from the battery through the wire 48, contact 50, the train, contact 50^a, wire 56 to one terminal of the electro-magnet 53 and from the second contact of the electro-magnet to the battery through the wire 62. The armature 61 of the electro-magnet is thereby attracted, elevating the switch blade 60 so that it is engaged with the latch notch 59 and held in its elevated position, the circuit to the electro-magnet 52 having been broken at this time. As the train continues during its passage over the rail sections 44, 45, it completes the circuit between the contacts 51, 51^a, completing the circuit to the electro-magnet 52, as above described and again tripping the latch to permit the blade 60 to come into contact with the contact 54. Since, however,

the train has left the rail sections 42, 43, the signal remains inoperative. A second train entering the signal area will initially cause energization of the electro-magnet 52, but this operation will be ineffectual as the blade is already released. This operation, however, takes care of any accidental completion of the circuit between the contacts 50 and 50^a during the interval when no train is in the signal area.

It will, of course, be obvious that the construction hereinbefore set forth is capable of a certain range of change and modification without materially departing from the spirit of the invention and I accordingly do not limit myself to such specific structure except as hereinafter claimed.

Having thus described my invention, what I claim is:

1. In combination with an electrically operated signal for railway crossings, a right-of-way including a section in which the rails are insulated from the remainder of the right-of-way and from one another, a normally closed switch, a source of E. M. F., a circuit including said rails, the switch, the source of E. M. F. and the signal, a train controlled latch for maintaining the switch in open position and controlled by a train to release the switch prior to entering and after leaving said section and train operated means controlled by the train while in said section for moving the switch to a position where it is engaged by said latch.

2. In combination with an electrically operated signal for railway crossings, a right-of-way including a section in which the rails are insulated from the remainder of the right-of-way and from one another, a normally closed switch, a source of E. M. F., a circuit including said rails, the switch, the source of E. M. F. and the signal, a train controlled latch including an electro-magnet and a bell crank lever actuated thereby for maintaining the switch in open position and controlled by a train to release the switch prior to entering and after leaving said section and train controlled means including an electro-magnet controlled by the train while in said section for moving the switch to a position where it is engaged by said latch.

In testimony whereof he affixes signature.

JOHN A. MORRISON.
